CONTROL MEANS

Lester A. Grimes, New Rochelle, N. Y., assignor
to The Reliable Automatic Sprinkler Co., Inc.,
Mount Vernon, N. Y., a corporation of New
York

Application June 13, 1947, Serial No. 754,581

23 Claims. (CL. 169—20)

This invention relates to control means and particularly to means for controlling the alarms for automatic sprinkler systems and the like, although certain features of the invention are of broader application.

Conventional automatic sprinkler systems of the wet pipe type comprise an alarm check valve in the water line leading to the sprinklers, an alarm, and a retard device for controlling the alarm. The conventional retard device controlling the alarm consists of an accumulation retard chamber with the control of the alarm being responsive to the volume of water in the chamber.

One object of the invention is a novel and improved retard control means which has the advantage among others of operating responsively to pressure as distinguished from the volumetric response.

A further object of the invention is a novel and improved retard control means which is characterized among other things by the control of multiple alarms which are independently adjustable as to time elements.

A further object of the invention is a novel and improved retard control means which is characterized by its dependability, accuracy and reliability in operation.

A further object of the invention is a novel and improved retard control means which is characterized by its compactness and the facility with which it may be installed and adjusted.

A further object of the invention is a novel and improved retard control means comprising a main control element having contractile and expandable chambers with a suitable fluid sealed therein with at least one of said chambers being responsive to pressure surrounding the same.

A further object of the invention is a control unit having sealed fluid chambers with a restricted transfer passage therebetween and with certain of the chamber walls flexible to permit contraction and expansion of the chambers together with means for supplying fluid pressure to the flexible wall of one of said chambers.

Further objects of the invention will herein-after appear.

For a better understanding of the invention, reference may be had to the accompanying drawings forming a part of this application, wherein

Fig. 1 is a sectional view thereof;

Fig. 1A is an enlarged sectional view along the line 1A—1A of Fig. 1;

Fig. 2 is a section through the casing thereof;

Fig. 3 is a view of an alarm device which may be used with the invention; and

Fig. 4 is a view illustrating an alarm check valve which is usable with the invention.

Referring to the drawings, I have shown the invention in an embodiment comprising a casing 1 having a lower chamber 2, an upper chamber 3, a cylindrical bore 4 below the chamber 2, an outlet 5 from the bore 4 leading to a motor alarm device, and a drain 6 substantially in line with the outlet 5 and communicating with and disposed on the opposite side of the bore 4. The casing comprises a part 1' to one side thereof and having a chamber 7 in communication through an opening 8' with the chamber 2. A fluid pressure inlet 8 is provided above the chamber 7 and communicates with the chamber 7 through the passage 8'. The chamber 7 comprises a cylindrical filter element 9 with its upper end alined with the opening 8' and the fluid pressure upon entry into the chamber 7 first passes into the central portion of the filter 9 and then into the chamber 7 from whence it flows to the chamber 2.

An important feature of the invention is the control unit A housed in the casing and cooperatively functioning with the chambers 2, 3 and 4 to effect the controlling functions. This element A comprises upper and lower chambers 11 and 12 which are sealed to the outside and contain a suitable fluid. These chambers 11 and 12 are contractile and expandable with one of the chambers expanding while the other is contracting and vice versa. The chambers 11 and 12 are spaced and separated from each other by means of a disc head 13, this head comprising an annular flange 14 on its outer edge for mounting the unit A centrally of the casing. The unit A is supported by an annular shoulder 16 formed on the inner wall of the casing, the annular flange 14 of the spacing and separating head 13 resting upon the shoulder 16 with an annular gasket 17 disposed between the flange 14 and the shoulder 16 for the purpose of making a fluid pressure tight joint between the disc head 13 and the shoulder 16. The interior of the casing in the vicinity of the disc head 13 is screw threaded to receive an annular holding and clamping nut 18, this nut 18 being screwed down tightly against the annular flange 14 to put the gasket 17 under compression. The clamping nut 18 is provided with suitable notches or other means 18' for facilitating the tightening or loosening of the nut 18. The disc head 13 is provided with a central hub part or thickened portion 19 and this hub part is provided with means restricting the flow of fluid from one of the chambers 11 and 12 to the other,

and this restricted passage in the particular embodiment shown is a clearance between a rod or stem 20 passing through a central opening formed in the hub part 19. The stem or rod 20 passes freely through the central opening with the predetermined clearance therebetween and the walls of the central opening 19' formed through the hub part 19. The disc head 13 forms the bottom end wall of the chamber 11 and the top end wall of the chamber 12. One of the side walls or outer end walls is flexible so as to expand one chamber while the other chamber is being contracted and in the particular embodiment shown the side walls which are indicated at 11' and 12' respectively are formed bellows-like with the end walls formed of heads 21 and 22. The side walls 11' and 12' are of cylindrical shape with the bellows-like wall 11' being fastened to and sealed fluid pressure tight to the upper end head 21 and likewise fastened and sealed fluid pressure tight to the upper side of the disc head 13 while the side walls 12' of the lower chamber 12 is likewise fastened and sealed fluid pressure tight to the under surface of the disc head 13 and to the upper surface of the disc head 22. The bellows under head 21 is provided with a central downwardly depending part or projection 21' and it screw threadedly receives the upper end of the rod or stem 20 while the bellows head 22 is provided with a central screw threaded opening to receive the lower end of the rod or stem 20. The flow or transfer of fluid from one chamber 11 to the other through the clearance at the central opening 19' tends to compel the two heads 21 and 22 to move in unison and the rod or stem 20 makes this action more positive.

The lower bellows head 22 is provided underneath with a central stem extending downwardly therefrom which stem is externally screw threaded and there is screw threadedly attached to this a valve support member 23, the latter having a central bore which is screw threaded for adjustment on the stem. This valve support member 23 at its upper end is provided with a flaring valve portion 24 which cooperates with the upper interior surface 25 of the bore 4 to form a control valve with the valve opening gradually increasing as the rod or stem 20 and the valve support 23 are moved upwardly. A compression spring 26 is shown disposed between the downwardly extending stem carried by the valve head 22 and the lower wall surface of the bore of the support member 23 which spring assists in taking up any lost motion in the threaded connection, thereby tending to lock the member 23 in the adjusted position.

A small drain passage or opening 6 leads from the bore 4 into the drain outlet 67 and the valve support 23 carries at its lower end an enlarged cylindrical valve member 28 and this valve portion 28 substantially closes the small drain outlet 6 when the valve portion 28 occupies the position to block or substantially block the drain opening 6 as, for example, when the end head 22 is moved upwardly to cause the valve portion 28 to thus function. The bellows 11' and 12' with their closing heads 21 and 22 and the central disc 13 form an upper and a lower sealed chamber for the reception of a suitable fluid as, for example, glycerine or oil. The central hub portion 19 of the disc 13, in addition to the clearance between the walls of the opening formed therein and the rod or stem 20, is provided with one or more vertical passages 30 for permitting the flow of

fluid from the upper chamber 11 to the lower chamber 12 and in the particular embodiment shown there are four of these passages 30. The lower side of the hub portion 19 is screw threaded to receive a sleeve 31 which is similarly screw threaded on the interior thereof to cooperate with the under side of the hub portion 19. Also the upper side of the central hub part 19 is exteriorly threaded to receive a similar internally threaded sleeve 32. Both of these sleeves 31 and 32 form stops to limit the degree of contraction and expansion of the chambers 11 and 12, namely the degree of collapsing and expansion of the bellows. That is the bellows head 21 is engaged by the upper end of the sleeve 32 and the lower bellows head 22 is engaged by the lower end of the sleeve 31 at the limits of movement.

The lower sleeve 31 has the additional function of supporting a valve housing and mechanism on the inside for controlling the drain passages 30. This valve mechanism includes an open ended housing 35 which is provided with screw threads at its upper and open end to engage cooperating internal threads of the sleeve 31 as shown at 31'. A valve element 36 which is of inverted cup shape form is provided for controlling the transfer passages 30. This valve element 36 is provided with a central opening through the bottom thereof for the accommodation of the rod or stem 20 and this valve element slides freely within the sleeve housing 35. The upper part of the valve element 36 is therefore of annular shape and is adapted to close the passage or passages 30 when the valve element 36 is in the uppermost position. It is normally held in the uppermost position to close the passage or passages 30 by a compression spring 37 engaging at one end the interior of the valve element 36, namely at its upper end and engaging the closed end of the sleeve housing 35 and this spring 37 surrounds the rod or stem 20. The latter passes freely through the central opening of the hub part 19 of the disc 13, through the central opening of the valve member 36, the spring 37 and the opening formed in the bottom of the sleeve-like housing 35 thereby permitting free and unhindered movement of the rod or stem 20 under the influence of the actuating means including the head 22 and a compression spring 40.

Fig. 1 shows the parts of the control means approximately in the relative position or positions that they assume when there is no fluid pressure being received in the chamber 2 through the intake 7', 8, 8' as, for example, from an alarm check valve. In this position the chamber 12 is fully expanded, namely the bellows 12' is fully extended to the predetermined limit, while the chamber 11 is fully contracted, namely the bellows 11' is collapsed to its fullest predetermined extent, that is the bellows head 21 is in engagement with the upper end of the sleeve 32 while the bellows head 22 is supported in the position shown from the lower end of the sleeve 31.

Means are provided for biasing the heads 21 and 22 in a downward direction. This is effected by means of the compression spring 40 surrounding a sleeve 41 and engaging at its lower end a flange 42 formed on the lower end of the sleeve 41 and engaging at its upper end an adjustable nut 44 carried by the casing. The sleeve 41 is provided at its upper end with an inwardly extending flange 43 which engages the cylindrical head 21 at its upper surface around the periphery thereof. The lower edge of the adjustable nut 44 forms an abutment of the casing against which the upper end of the compression spring 40 engages and in

the particular embodiment shown the sleeve 44 is screw threaded on its exterior for cooperation with an internally threaded portion of the upper end of the casing 1. By adjusting the position of this abutment sleeve 44 the tension of the spring 40 may be adjusted to obtain the desired regulation and control.

The control mechanism is utilized for controlling or effecting the operation of a suitable alarm or alarms as, for example, for use in automatic sprinkler systems. As indicated above this control means may be used either to control or operate an electrically operated alarm or a mechanically operated or a power operated alarm or may be used for controlling or operating two or more alarms simultaneously.

For this purpose the head 21 carries an actuating rod or stem 45 which projects upwardly out of the chamber 3 of the casing 1. In the particular embodiment shown this actuating or controlling rod or stem 45 is screw threadedly attached as indicated at 45' to the head 21 by means of a central opening formed in the head 21, this opening and the lower end of the rod 45 being screw threaded for this purpose. This rod or finger 45 is thus adjustably supported by the head 21 and a locking nut is illustrated for locking the rod or finger 45 to the head 21 in any adjusted position. A closing cap and adapter 60 is screw threadedly attached as indicated at 61 to the upper end of the casing 1 and this cap is provided with a central screw threaded opening for the attachment of an alarm control as, for example, like that shown in Fig. 3 or for the attachment of a thimble 62 when the rod 45 is not being used to control an alarm. When the rod 45 is to be used to control or actuate an alarm the thimble 62 is removed and the alarm such as that shown in Fig. 3 is attached to the adapter 60 in the place of the thimble 62. When the alarm control illustrated in Fig. 3 is employed and to be controlled or operated by the rod 45 the nipple 54 of the casing of the alarm device illustrated in Fig. 3 is attached into the screw threaded opening of the closing cap and adapter 60.

The frame or casing of the electric alarm illustrated in Fig. 3 is formed of three elements including a lower main supporting member comprising the screw nipple 54 and a base 55. The lower part of this base is formed with an opening 46 leading into a similar smaller opening 46' formed in the base or upper part 55 of the main base which opening accommodates freely the control rod 45. Another main body or casing element is the disc-like member 56 having a downwardly extending flange 56' for screw threaded attachment to the base part 55 of the base support. The body part 56 is dished out at its under surface as indicated at 57 while the upper part 55 of the base is provided with a central cylindrical depression 55'. The dished out body member 56 and the recess or depression 55' in the portion 55 form a chamber between the elements for the accommodation of a diaphragm 47 clamped between the base portion 55 and the body member 56. The third element of the casing is a cover or closure cap 58 which is fastened to the body element 56 by screw bolts 59 with the rim of the cover or closure cap 58 resting on a shoulder or ledge 59' formed on the upper side of the body member 56 at its periphery.

The electric alarm shown in Fig. 3 is adapted for use with either the control means of this invention or it may be used with conventional retard accumulator chamber controls. When used

with the latter controls it is desirable to form a watertight seal and this is effected by the clamping of the gasket 47' on one side of the diaphragm and in the particular embodiment shown the gasket is below the diaphragm.

Housed within the closure cap or cover 58 is an electric contact control including a conventional mercury switch 50 which is suitably mounted on and carried by a lever 49 which is pivotally mounted at 49' to a bracket projection on the upper side of the body. A spring 51 is provided on one side of the pivotal point 49' of the lever 49 to bias the switch member 50 in counter-clockwise direction while the lefthand end of the lever 49 is provided with a downwardly extending stop 52 to limit the upward movement of the righthand part of the lever 49 under the influence of the spring 51. The spring 51 is disposed beneath the righthand end of the lever 49 and engages at its ends bosses formed on the under side of the lever 49 and on the upper side of the member 56 for anchoring the spring in position. The diaphragm 47 carries a plunger 48 which is guided in a corresponding chamber formed in an upwardly projecting part of the body member 56 and this plunger 48 carries a pointed actuating part 48' which is adapted to engage the under side of the lever 49 at a point to the left of the pivotal point 49', 20 the actuating part 48' passing up through a suitable opening as illustrated. When the actuating rod or stem 45 is moved upwardly by the control illustrated in Fig. 1 the upper end of the rod member 45 engages the diaphragm 47 and the 25 central part of the diaphragm 47 together with the plunger 48 are thereby moved upwardly to actuate the lever 49 clockwise about the pivotal point 49' and by such actuation of the lever 49 the mercury switch effects the desired alarm 30 operation or control.

A bleeder or drain opening 53 is illustrated for relieving pressure underneath the diaphragm 47 in certain installations with which the electric alarm of Fig. 3 is adapted to be used, as for 35 example with the retard accumulator chambers referred to above. When a water motor or other mechanical alarm is to be controlled or operated by fluid pressure the valve support and actuating member 23 is adjusted relatively to the upper end 45 of the bore 4 so as to bring the valve cooperating parts or elements 24 and 25 to the exact relative position desired, that is this adjustment is adjusted to pass the fluid pressure for operating or controlling the water motor or mechanical 50 alarm at a predetermined upward movement of the head 22 under the influence of the fluid pressure in the chamber 2. By adjusting the valve support member 23 upwardly the time period is shortened and by adjusting it downwardly the 55 time period is increased. The time period for operating the alarm control is thus adjustable and moreover independently of the adjustment of the alarm controlling rod or stem 45.

For convenience in adjusting the position of the valve support member 23 the bore 4 is continued to the bottom of the casing 1 to form a screw threaded opening at the lower portion thereof and a closing plug 65 is removably inserted in the lower part of the bore to permit the entry of a conventional tool for rotating the member 23. The lower end of the valve support member 23 is provided with a groove or notch 66 whereby the same may be engaged by a screw driver or the like for adjustment.

The bore 4 is provided with a suitable drain

opening 6, this drain opening 6 leading to the drain outlet 61 with which means are provided for attaching a suitable drain connection. The fluid pressure for controlling or actuating the alarm passes from the bore 4 through the outlet port 5 into the outlet 68 and the latter is tapped at its outer portion as indicated at 68 for the reception of a suitable connection for supplying the fluid pressure to the mechanical alarm or actuator device which may be as indicated above a water motor or any suitable or conventional fluid pressure controlled or operated means. The drain 6 is controlled by a second valve element 28 carried at the lower end of the valve support member 23. This valve element 28 in the particular embodiment shown is formed integrally with the valve support element 23 and makes a sufficiently close fit with the bore 4 to substantially close the drain passage 6 without offering any frictional resistance to the upward movement of the valve support 23. In the adjustment as shown in Fig. 1 the valve element 28 is disposed slightly below the drain passage 6 but when the valve element 28 is moved upwardly the drain passage 6 is substantially closed. In the particular embodiment shown the valve support 23 is formed with a cross opening 70 just above the valve element part 28 while the latter is provided with a central downwardly extending passage 71, putting the cross passage 70 in direct communication with the chamber below the valve element 28. This arrangement prevents the entrapment of fluid pressure and assures free and unhindered movement of the valve support 23.

The operation of the control means of this invention is generally as follows. As soon as fluid under pressure begins to flow to the chamber 2 through the intake 8 fluid pressure brings to act on the bellows head 22, tending to collapse or partially collapse the bellows 12' and to move the head 22 with the stem or rod 20 upwardly. This upward movement is resisted by the resistance to flow of the fluid through the restricted passage or clearance about the rod or stem 20 at the hub part 19 of the disc member 13 and is also resisted by the tension of the spring 40. If the fluid pressure supplied to the chamber 2 continues long enough, depending upon the period of adjustment the actuator 45 is moved upwardly sufficiently to actuate the alarm described above. This time period depends on the adjustment of the actuating rod 45, and the clearance about the rod or stem 20 at 19 together with the tension of the spring 40. If the supply of fluid pressure to the lower chamber 2 should be discontinued before the predetermined time period is up then the alarm operated by the actuator 45 is not operated. This applies also to the fluid pressure alarm control which will be described below. Whenever this happens, namely when fluid pressure is lowered or the supply of it to the chamber 2 is discontinued the compression spring 40 instantly takes over control, forcing the head 21 (and the head 22) downwardly, thereby creating pressure within the bellows 11' which pressure is sufficient to open the valve element 36 against the tension of the spring 37, whereupon the fluid which had been transferred from the lower bellows 12' to the upper bellows 11' is rapidly and quickly retransferred back to the bellows 12' through the passages 30 which are controlled by the valve 36. This control whereby the return of the transferred fluid may not only flow downwardly through the clearance 19' but also through the

passage or passages 30 minimizes the resistance to the return to the normal position shown with the head 21 engaging the upper end of the sleeve 32 as it stops. When this occurs the pressures in the chambers formed by the bellows are equalized and the valve 36 is again closed by the spring 37.

The fluid under pressure which has accumulated in the lower chamber 2 of the casing around about the bellows 12' drains off through the slight clearance maintained in the adjusted position between the valve elements 24 and 25 into the bore 4 and thence through the drain passage 6.

The operation is generally the same when the water motor or other fluid pressure alarm actuating or controlling device is employed. The moment the fluid under pressure begins to flow into the chamber 2 to exert pressure underneath the head 22, the latter tends to move in an upward direction. When the movement takes place the valve opening between the valve element 24 and the surface or valve part 25 is increased in area whereupon the fluid pressure then escapes in sufficient quantity after a predetermined time period down into the bore 4 and out through the opening 5 leading to the water motor or other alarm control device to control or actuate the same.

As indicated above I have thus provided a multiplicity of alarm controls. There are two such controls in the particular embodiment shown and these controls are independently adjustable and may be set for operation at the same time period or at different time periods.

In Fig. 4 I have illustrated the control means of this invention as operatively associated with an alarm check valve 75 which is set forth and claimed per se in an application for United States Letters Patent entitled Valves for Automatic Sprinkler Systems and executed by me on May 29, 1947. The control means of this invention is particularly adapted for use with the alarm check valve 75. The latter embodies a valve clapper 76 having a rubber or other suitable facing 77 which is clamped to the upper plate of the clapper by a plate 78. The clapper is carried by a clapper arm 79 with the clapper being journaled in the bearings 80 of the clapper arm for free rotation about the valve seat. The valve includes a valve seat ring 81 which is integrally formed with the valve body or casing as by being cast integrally therewith. This cast in ring 81 has built up on the seating surface thereof a non-rust or non-ferrous valve seating surface 82 and the valve seat ring including the non-ferrous surface is provided with an alarm port or passage 83 of short or abbreviated circumferential extent as, for example, having a cross sectional area approximating that of the outlet port 84. The latter is connected by a pipe 85 with the intake 8 of the control means described above. It is intended that the disclosure of the above application describing and illustrating the alarm check valve 75 shall be considered as a part of the disclosure of this application. The fluid used in the sealed chambers 11 and 12 is preferably an inelastic one. The clearance 19' between the stem 20 and the wall of the central opening of the disc head 13 is only a few thousandths of an inch, depending somewhat on the viscosity of the fluid used. This clearance 19' is exaggerated in Fig. 1A for purposes of illustration. In the particular embodiment the corrugated or bellows-like walls 11' and 12' are shown as having the same number of corrugations and of being the

same length when freely extended but it is understood that they may be of a different number of corrugations or they may be of different lengths with the corrugations closer together, as may be desired.

I claim:

1. A retard control means for automatic sprinkler systems comprising a casing, a pair of sealed contractile and expansible fluid chambers filled with a suitable fluid mounted in said casing with a restricted passage between the chambers permitting the gradual transfer of fluid from one chamber to the other when one of the chambers is contracted, one of said sealed chambers being disposed in a fluid pressure receiving chamber formed in the casing and being contractile by the fluid pressure received therein to cause a portion of the fluid in the sealed chamber to transfer through the restricted passage into the other sealed chamber, an alarm control means actuated by the contraction of one sealed chamber and a valve means operated by difference in pressures in the two sealed chambers permitting a quick return of the transferred fluid when the fluid pressure supply is reduced or discontinued in the casing.

2. A retard control means for automatic sprinkler systems comprising a casing, a pair of sealed contractile and expansible fluid chambers filled with a suitable fluid mounted in said casing with a restricted passage between the chambers permitting the gradual transfer of fluid from one chamber to the other when one of the chambers is contracted, one of said sealed chambers being disposed in a fluid pressure receiving chamber formed in the casing and being contractile by the fluid pressure received therein to cause a portion of the fluid in the sealed chamber to transfer through the restricted passage into the other sealed chamber, an alarm control means actuated by the expansion of one sealed chamber and a valve means operated by difference in pressures in the two sealed chambers permitting a quick return of the transferred fluid when the fluid pressure supply is reduced or discontinued in the casing.

3. A retard control means for automatic sprinkler systems comprising a casing, a pair of sealed contractile and expansible fluid chambers filled with a suitable fluid and mounted in said casing with a restricted passage between the chambers permitting the gradual transfer of fluid from one chamber to the other when one of the chambers is contracted, one of said sealed chambers being disposed in a fluid pressure receiving chamber formed in the casing and being contractile by the fluid under pressure received therein to cause a portion of the fluid in the sealed chamber to transfer through the restricted passage into the other sealed chamber, an alarm control means actuated by the contraction or expansion of one sealed chamber, biasing means opposing the contraction and expansion of the sealed chambers, a valve port between the sealed chambers and valve means controlling said port and responsive to the difference in pressure in the sealed chambers set up by the biasing means to cause a quick retransfer of the fluid from one sealed chamber to the other when the fluid pressure is reduced or discontinued in the casing fluid pressure chamber.

4. A retard control means for automatic sprinkler systems comprising a casing, a pair of sealed contractile and expansible fluid chambers filled with a suitable fluid and mounted in

said casing with a restricted passage between the chambers permitting the gradual transfer of fluid from one chamber to the other when one of the chambers is contracted, one of said sealed chambers being disposed in a fluid pressure receiving chamber formed in the casing and being contractile by fluid under pressure received therein to cause a portion of the fluid in the sealed chamber to transfer through the restricted passage into

10 the other sealed chamber, an alarm control means actuated by the contraction or expansion of one sealed chamber, biasing means opposing the contraction and expansion of the sealed chambers and normally holding the sealed chambers in a position in which the sealed chamber disposed in the fluid pressure chamber of the casing is expanded to a predetermined position and the other sealed chamber is partially contracted, a valve port between the sealed chambers and valve control means for said port which is opened under the pressure created by the biasing means to open the port and thereby permitting a quick retransfer of fluid when the fluid pressure supply is reduced or discontinued in the casing fluid pressure chamber.

15 5. A retard control means for automatic sprinkler systems comprising a casing, a pair of sealed contractile and expansible fluid chambers filled with a suitable fluid and mounted in said casing, one of said sealed chambers being disposed in a fluid pressure receiving chamber formed in the casing and being contractile by the fluid pressure received therein, an alarm control means actuated by the contraction or expansion of one sealed chamber and means comprising communicating passages between said sealed chambers and a valve control for permitting a gradual transfer of a portion of the fluid from the sealed chamber which is disposed in

20 the fluid pressure chamber of the casing when fluid pressure is received therein and permitting the quick retransfer of the fluid when the fluid pressure supply in the casing chamber is reduced or discontinued.

25 6. In a control means of the character set forth in claim 5 wherein the sealed chamber which is disposed in the casing fluid pressure chamber carries a valve controlling a port between said sealed pressure chamber and a mechanical alarm.

30 7. In a control means of the character set forth in claim 5 wherein one of the sealed chambers carries a valve element controlling a port leading to a fluid actuated alarm.

35 8. In a control means of the character set forth in claim 5 wherein one of the two sealed chambers carries a means for operating an electric alarm.

40 9. In a control means of the character set forth in claim 5 wherein the sealed chambers are spaced from each other by a head member and said head is provided with said communicating passages, and a biased valve is provided for controlling at least one of said passages and is adapted to close the same upon the contraction of one of the chambers and to open the same upon the contraction of the other chamber.

45 10. In a control means of the character set forth in claim 5 wherein the sealed chambers are formed with corrugated side enclosing walls and end head closures together with a disc head member separating the chambers, said disc head member having an opening therethrough with a stem passing through and having a small clearance with said opening and mechanically connecting the end heads, said disc head having

one or more communicating passages therein between the two sealed chambers with the valve control comprising a spring biased valve element controlling said passages.

11. In a control means of the character set forth in claim 5 wherein the sealed chambers are formed with corrugated side enclosing walls and end head closures together with a disc head member separating the chambers, said disc head member having an opening therethrough with a stem passing through and having a small clearance with said opening and mechanically connecting the end heads, said disc head having one or more communicating passages therein between the two sealed chambers with the valve control comprising a spring biased valve controlling said passages and spring biasing means are provided for biasing the end heads in one direction against a stop member.

12. In a control means of the character set forth in claim 5 wherein independently adjustable actuating means for the alarms are actuated by the contraction and expansion of said sealed chambers.

13. A retard control means for automatic sprinkler systems comprising a casing having a fluid pressure receiving chamber therein, a sealed unit having a pair of sealed chambers formed of corrugated side walls permitting endways contraction and expansion of the chambers, the corrugated walls thereof being sealed to a central member separating the two sealed chambers with the outer ends thereof sealed to end closing heads, said central member being fixedly mounted in the casing and sealing the fluid pressure receiving chamber thereof from the upper part of the casing with one of said sealed chambers projecting down into the fluid pressure receiving chamber and subject to the fluid pressure therein, stop means limiting the contraction and expansion of the chambers, biasing means holding the end head of the upper sealed chamber in a fixed position with the chamber thereof partially contracted and with the sealed chamber which is disposed in the fluid pressure receiving chamber of the casing expanded, alarm control means actuated by the contraction and expansion of the sealed chambers, and communicating passages formed in said central member between the sealed chambers and a valve control for permitting only a gradual transfer of a part of the fluid from the lower sealed chamber to the upper chamber when the lower sealed chamber is subjected to the fluid pressure in the fluid pressure receiving chamber but permitting a more rapid retransfer of the fluid from the upper chamber to the lower chamber when the fluid pressure is reduced or discontinued in said fluid pressure receiving chamber.

14. A control unit of the character set forth comprising a pair of sealed contractile and expansible fluid chambers separated by and sealed to a head with a restricted passage therein between the chambers permitting the transfer of fluid from one chamber to the other, certain of the enclosing walls of said chambers being movably flexible for permitting the expansion and contraction of the chambers by transfer of fluid through the restricted passage, means for applying fluid pressure to the exterior of one of said chambers to cause contraction and expansion of the chambers and control means actuated by said contraction and expansion of the chambers.

15. A control unit of the character set forth comprising a pair of sealed contractile and expansible fluid chambers separated by and sealed to a head with a restricted passage therein between the chambers permitting the transfer of fluid from one chamber to the other, certain of the enclosing walls of said chambers being movably flexible for permitting the expansion and contraction of the chambers by transfer of fluid through the restricted passage, means for applying fluid pressure to the exterior of one of said chambers to cause contraction and expansion of the chambers and control means actuated by said contraction and expansion of the chambers, said flexible and movable portions of the chamber enclosing walls being mechanically connected for operation in unison.

16. A control unit of the character set forth comprising a pair of sealed fluid chambers with a restricted passage therebetween permitting the transfer of fluid from one chamber to the other, said chambers being provided with collapsible side walls and rigid end heads, means for mounting said chambers with one of said chambers disposed in a chamber adapted to receive fluid pressure for collapsing the walls thereof and effecting a delayed movement of the end head of the other sealed chamber through the delayed transfer of fluid through the restricted passage and a control element operated by the end head of said last named chamber.

17. A control unit of the character set forth comprising a casing having a chamber therein adapted to receive fluid pressure and a control unit having sealed fluid chambers separated from each other by a wall having a restricted passage therethrough permitting the transfer of fluid from one chamber to the other, said chambers having enclosing walls certain portions of which are flexible and movable for contraction and expansion of the chambers, one of said chambers being disposed in a fluid pressure receiving chamber and means responsive to the flexing and movement of the flexible and movable part of the enclosing walls of one of said sealed chambers for effecting a controlling function.

18. In a control of the character set forth in claim 5 wherein the sealed fluid pressure chambers carry an adjustable valve disposed in a bore in the casing, said valve being adjustable by the application of a suitable tool into the bore.

19. A control unit of the character set forth comprising a pair of contractile and expansible chambers formed by side corrugated walls permitting endwise contraction and expansion of the chambers, closing end heads, an intermediate support member, stop members attached to the intermediate member, one of said stop members being a housing sleeve for a valve control, a valve housing carried by said sleeve, a spring biased valve housed in said housing and engaging a portion of the surface of the intermediate member, said portion having one or more communicating passages controlled by said valve element and a stem passing through a central opening formed in the intermediate member with a small clearance therebetween.

20. A control unit of the character set forth comprising a pair of contractile and expansible chambers formed by side corrugated walls permitting endwise contraction and expansion of the chambers, closing end heads, an intermediate support member, stop members attached to the intermediate member, one of said stop members being a housing sleeve for a valve control, a valve

housing carried by said sleeve, a spring biased valve housed in said housing and engaging a portion of the surface of the intermediate member, said portion having one or more communicating passages controlled by said valve element and said intermediate member having a restricted passage leading therethrough from one chamber to the other and maintaining the chambers in communication with each other therethrough.

21. A retard control means for automatic sprinkler systems comprising a casing, a plurality of contractible and expansible fluid pressure chambers mounted in said casing with a restricted passage means between at least two of said chambers for gradually transferring fluid from one chamber to another when one of the chambers is contracted or expanded, one of said chambers being disposed in a fluid pressure receiving chamber formed in the casing and being contractible and expansible responsively to the fluid pressure in said fluid pressure receiving chamber to cause an interchange of fluid from one of the contractible and expansible chambers to the other, an alarm control means actuated by said contractible and expansible chambers and valve means operated by differences in pressure in the two expansible and contractible chambers permitting a quick return of the transferred fluid when the fluid pressure supply is reduced or discontinued in the casing.

22. Control means for automatic sprinkler systems comprising a casing, a plurality of contractible and expansible fluid pressure chambers

5 mounted in said casing, means for transferring fluid from one chamber to the other when certain of the chambers are contracted and expanded, one of said chambers being disposed in a fluid pressure receiving chamber formed in the casing and being contractible and expansible by the changing fluid pressure received therein, control means actuated by said contractible and expansible fluid chambers and valve means operatively responsive to differences in pressure in certain of the contractible and expansible chambers permitting a quick equalization of fluid pressures in certain of the chambers.

10 15 20 25 23. A control unit for automatic sprinkler systems comprising a casing, a plurality of separate expansible and contractible fluid pressure chambers formed into a unit and mounted in said casing, means for transferring fluid pressure between certain of said chambers including valve control means responsive to differences in pressure therein and a control means actuated by said unit.
